BACKGROUND OF THE INVENTION**(1) Field of the Invention**

The invention relates to garments that are worn that provide sweat relief, display useful information and have a tight fit by means of an elastic connection.

(2) Description of the Related Art

Sweat bands in general have been known in the sports environment for years. In sports, for example, athletes have been known to wear different color head bands or arm bands in order to display their individuality, or demonstrate style. Many of these different sweat bands are the same color as the player's team color, however, there is an absence of sweat bands designed to display useful information, such as the player's jersey number, a particular product that they desire to endorse, or a political message.

U.S. Pat. No. 5,802,608 to Earl discloses a waistband with an elastic belt for identifying athletes during sports events. However, the invention of Earl is designed for the waist in particular, and the display portion hangs loosely from the elastic belt rather than being secured by elastic means on both sides. The displaying portion could easily be torn off. In addition, the displaying means used in Earl is not consistent with the current style of athletes.

U.S. Pat. No. 5,901,379, to Harata discloses a sweat band that wraps around the arm. However, it is connected by a fastener, rather than by elastic means, and does not include any display means.

U.S. Pat. No. 5,823,012 to Hacskeylo discloses an athletic band, however, the displaying means are integrated on the band, and not connected to the band by elastic means.

U.S. Pat. No. 4,918,758 to Rendina discloses a stretch band with display means. However, the display means are removably attached to the stretch band by Velcro® rather than by elastic means.

U.S. Pat. No. 5,826,277 to McConville also discloses a stretch band with display means. However, the display means are directly stitched upon the band rather than being connected by elastic means.

BRIEF SUMMARY OF THE INVENTION

This invention relates to a sweat band, and a display that is attached by elastic means to the sweat band. The sweat band, the elastic means, and the display can be made from the same materials. The elastic means provides for a tight fit on the body, and a tight connection between the sweat band portion and the display portion. The elastic means can be made from any elastic material. The garment can be designed and worn for any portion of the body, but the preferred use is for the arm. The display and the sweat band are made of any common perspirant-absorbing materials. For example nylon, cotton, or spandex would suffice. The display has information attached to it, such as a player's number. This information can be attached to the display by any convention means, such as stitching, or by

Velcro (registered trademark). The information could also be designed so as to be integrated to the display. The elastic means, sweat band and display can be designed in different stylish shapes, however they will still serve the same functional purpose.

BRIEF DESCRIPTION OF THE SEVERAL VIEWS OF THE DRAWINGS

FIG. 1 is an front elevation view of a first embodiment of the invention shown in its operating environment.

FIG. 2 is a top view of the garment shown in FIG. 1.

FIG. 3 is an front elevation view of a second embodiment of the invention shown in its operating environment.

FIG. 4 is a rear elevation view of the first and second embodiments of the invention shown in its operating environment.

DETAILED DESCRIPTION OF THE INVENTION

A first embodiment of the invention is illustrated by FIGS. 1-2, and 4. The invention is referred to generally by 1 is worn on a human arm 10. The display 2 displays the information 8 that is designed on the display. In this first embodiment, display 2 is designed as a basketball, and the information displayed 8 is the number twenty-one. However display 2 could be any design, and the information 8 could be any number, or any message or shape. There could optionally be no information 8 displayed. The information 8 could be attached to display 2 by stitching means, Velcro® means, glue means, or any known manner of attaching materials. The attachment could be releasable, by button means, or any other releasable connection means. The information 8 could also be designed to be integrated with the display 2 by using different color stitching for information 8 than is used for sweat band portion 3 when fabricating the invention 1. Any known means for designing garments that display a design integrally with the garment can be used. The display 2 and the sweat band portion 3 are made out of any perspiration absorbent material. The sweat band portion 3 can be any appropriate width or length. The elastic means are preferably four elastic strips 4-7 that are preferably rectangular, and can be attached to the display and the sweat band by any suitable means, such as stitching. Any suitable number of elastic strips could be used. Alternatively, the elastic strips 4-7 could be integrally designed with the sweat band portion 3, and display 2, rather than being separate. In this design, elastic strips 4-7, and display 2 could be made by cutting it out from a complete tubular sweat band.

A top view of the invention 1 is shown in FIG. 2. The top view shows that the information 8 protrudes a small amount from the display 2. However, in a possible alternative embodiment where information 8 is integrated to display 2, information 8 would not protrude from display 2.

FIG. 3 illustrates a second embodiment of the invention. In this embodiment, the display 2' comprises two basketballs (or any particular shapes) that are attached to each other and to sweat band portion 3', by any suitable means.

FIG. 4 illustrates a rear elevation view of the first and second embodiments of the invention 1 being worn on arm 10 of user. The rear section of the invention 1 is simply the sweat band portion 3.

In use, the present invention 1 is put onto the arm, head, leg, or whichever portion of the body where it is desired to be placed. The individual need only stretch the invention

over that particular portion of the body. The elastic material of the invention provides for a tight fit, and the display 2 displays useful information with a stylish look.

Although the present invention has been described with reference to preferred embodiments, one skilled in this art may make numerous revision in form and detail, and such revisions are intended to fall within the scope of the following claims. For example, any of the connections could be releasable, rather than permanent. Also, the information 8 could be on both sides of the display 2, so that the invention would be reversible.

What is claimed is:

1. An article to be worn by an individual comprising:
a sweat band portion with two ends,
elastic strips,
a display portion,
wherein said elastic strips connect said display portion with said sweat band portion at said two ends, and provide for a tight fit, and
wherein said elastic strips, said display portion, and said sweat band portion form a complete continuous tubular member.
2. The article of claim 1, wherein said elastic strips are connected to said sweat band portion and said display portion by stitching means.
3. The article of claim 1, wherein said elastic strips are integrally connected to said sweat band portion and said display portion.
4. The article of claim 1, wherein said display portion displays information that is attached to said sweat band portion and said display portion.
5. The article of claim 1, wherein said elastic strips are of a smaller width than the width of the sweat band.
6. The article of claim 1, wherein said elastic strips are four in number.
7. The article of claim 1, wherein said sweat band is made of perspiration absorbent material.
8. The article of claim 7, wherein said display is made of perspiration absorbent material.
9. The article of claim 8, wherein said elastic strips are made of perspiration absorbent material.
10. The article of claim 1, wherein said elastic strips, and said sweat band portion are made of elastic material.

11. The article of claim 10, wherein said display is made of elastic material.

12. The article of claim 1, wherein said sweat band, said elastic strips, and said display portion are made of perspiration absorbent material and elastic material.

13. The article of claim 10, wherein said display portion is in a shape and design of a basketball.

14. The article of claim 10, wherein said display is in the shape and design of two basketballs.

15. The article of claim 1, wherein said display portion displays useful information that is integrally connected to said display portion.

16. An article to be worn by an individual comprising:
a sweat band portion made of perspiration absorbent material with two ends;

displaying portion means made of perspiration absorbent material for displaying useful information;
elastic means for connecting said displaying means with said sweat band portion at said two ends and for providing a tight fit.

17. The article of claim 16 wherein said elastic means are at least two in number and have a smaller width than the width of said sweat band portion.

18. The article of claim 16 where said useful information is connected to said displaying portion in a releasable connection.

19. An article that is worn by an individual comprising:
a sweat band portion consisting essentially of one member with two ends,

a display portion comprised of one member,
elastic strips connected to said sweat band portion at said two ends,

wherein said elastic strips connecting said display with said sweat band portion, and
wherein said elastic strips, said display portion, and said sweat band portion form a complete continuous tubular member.

20. The article of claim 19 wherein said elastic strips are four in number, arranged in sets of two, and parallel to each other within said sets.
